CLAIM

The ornamental design for a currency acceptor, as shown and described.

DESCRIPTION

FIG. 1 is a perspective view of a first embodiment of a currency acceptor according to our design;

FIG. 2 is a front view thereof;

FIG. 3 is a left side view thereof;

FIG. 4 is a top view thereof;

FIG. 5 is a right side view thereof;

FIG. 6 is a rear view thereof;

FIG. 7 is a bottom view thereof;

FIG. 8 is a perspective view of a currency acceptor according to a second embodiment of our design which shows alternative features, the only difference being the configuration of the front;

FIG. 9 is a perspective view of a currency acceptor according to a third embodiment of our design which shows all of the alternative features, the only difference being the configuration of the front; and,

FIG. 10 is a perspective view of a currency acceptor according to a fourth embodiment of our design which shows all of the alternative features, the only difference being the configuration of the front.
